DESIGN FOR A KNIFE OR SIMILAR ARTICLE

Cecil H. Alexander, Grand Junction, Colo., assignor to Zip Clip Knife Corporation, Grand Junction, Colo., a corporation of Colorado

Application July 28, 1947, Serial No. 140,567

Term of patent 3½ years

(Cl. D22—3)

To all whom it may concern:

Be it known that I, Cecil H. Alexander, a citizen of the United States, residing at Grand Junction, in the county of Mesa, State of Colorado, have invented a new, original, and ornamental Design for Knife or Similar Article, of which the following is a specification, reference being had to the accompanying drawing, forming a part thereof.

Fig. 1 is a side elevational view of a knife, in closed position, showing my new design;

Fig. 2 is a side elevational view of the knife of Fig. 1, in open position;

Fig. 3 is a top plan view of the knife as illustrated in Fig. 2;

Fig. 4 is a top plan view of the knife as illustrated in Fig. 1; and

Fig. 5 is an end elevational view of the knife taken from the left of Fig. 1.

I claim:

The ornamental design for a knife or similar article, as shown.

CECIL H. ALEXANDER.
